UNITED STATES PATENT OFFICE.

GEOFFREY HOLT, OF LOS ANGELES, CALIFORNIA.

DESIGN FOR A BUFFET.

Application filed April 7, 1928. Serial No. 26,167. Term of patent 7 years.

To all whom it may concern:

Be it known that I, GEOFFREY HOLT, a citizen of Great Britain, residing at Los Angeles, in the county of Los Angeles and State of California, have invented a new, original, and ornamental Design for a Buffet, of which the following is a specification, reference being had to the accompanying drawing, forming a part thereof.

The figure of the drawing is a perspective view of the buffet showing my new design.

I claim:

The ornamental design for a buffet as shown.

GEOFFREY HOLT.
